H. C. SNOOK

ELECTRICAL CUT-OUT

Filed Sept. 8, 1921

Inventor:
Homer C. Snook,
by *Patent Office* Atty.

UNITED STATES PATENT OFFICE.

HOMER CLYDE SNOOK, OF SOUTH ORANGE, NEW JERSEY, ASSIGNOR TO WESTERN ELECTRIC COMPANY, INCORPORATED, OF NEW YORK, N. Y., A CORPORATION OF NEW YORK.

ELECTRICAL CUT-OUT.

Application filed September 8, 1921. Serial No. 499,267.

To all whom it may concern:

Be it known that I, HOMER CLYDE SNOOK, a citizen of the United States, residing at South Orange, in the county of Essex, State of New Jersey, have invented certain new and useful Improvements in Electrical Cut-Outs, of which the following is a full, clear, concise, and exact description.

This invention relates to electrical cut-outs, and particularly to the type of cut-out known as the electrical fuse.

It is customary, in electrical fuses, to surround the fuse conductor with a packing or filling material such as, for example, plaster of paris, sand, asbestos, silicic acid, or other suitable insulating substances which will protect the fuse sheath and nearby substances from fire or injury upon the premature or delayed disruption of the fusible conductor. It has been found highly desirable, if not absolutely essential, to pack the filler in a loose and evenly distributed mass about the fuse conductor in order to insure the ready diffusion of the liquid or vaporous metal which is liberated when the fuse blows. The use in electric fuses of such standard fillers as are mentioned above, no doubt diminishes the probability of fire due to the heating or explosion of the fuse sheath, but because of the great amount of filler needed to effectively quench the electric arc which is formed, it is necessary to resort to the inefficient and expensive alternative of employing fuses of large dimensions.

It is an object of this invention to provide an electric fuse which employs a comparatively small amount of insulating filler.

In accordance with its object, the present invention contemplates the use of a filling material adapted to rapidly adsorb the vapors liberated within the fuse casing when the fuse conductor melts or volatilizes. It has been found that silica gel, for example, has the peculiar property of readily adsorbing gases because of the very large surface which it has per unit of volume as compared with other substances, the large surface being in the form of very fine minute pores within the volume of the granules of the gel. Silica gel is an inorganic material and adsorbs or gives off gases by a reversible process which involves merely the changing of its temperature.

Another object of the invention is to pro-

vide a fuse which is extremely sensitive and which will blow quietly and immediately upon exposure for the requisite time to the prescribed overload.

It is a further object of the invention to provide a type of fuse which can be manufactured in commercial quantities with the desired degree of uniformity.

Other objects and features of the invention will appear from a consideration of the following description taken in conjunction with the accompanying drawing and the appended claims.

The drawing shows a longitudinal view, part in plan and part in section, of an electrical fuse of the cartridge type embodying the features of the invention. The invention is not limited, however, to this particular type of fuse.

Referring to the drawing, 1 represents the fuse conductor, of any suitable material, such as lead, arranged within a cylindrical casing 2, and attached by soldering or other suitable means to the terminal caps 3 at the point 4. The threaded extensions 5 of the caps 3 are each provided with a nut 6 as a means for connecting the fuse into an electrical circuit. The fusible wire 1 is surrounded with loose, dry particles of silica gel, shown at 7. The material 7 is a highly porous gel of silica which may be formed by mixing an acid, such as hydrochloric acid, with a sodium silicate solution, forming a colloidal solution of silicic acid from which the silicious compound sets to a gel. The concentrations of the acid and sodium silicate solution must be carefully determined, and care must be taken in bringing the two together in order to prevent a rapid coagulation due to the instability of the mixture. When the gel sets rapidly from the solution, it loses its adsorbent properties, rendering it useless for the purposes of the present invention. The gel formed in this manner may be broken, when dry, into small pieces and washed free from acid and salt. The water must be very carefully and slowly removed from the washed gel in order that the finished product may retain the highly porous structure which is exhibited by the gel while in solution. To accomplish this, the material may be subjected to gradually increasing degrees of heat in order that no sudden change may take place. It is to the

retention of its porous form and gelatinous structure that silica gel owes its remarkable property of adsorption which is not displayed by ordinary silicic acid or other fuse fillers. For the purposes of the present invention silica gel has been found to be more effective in quenching the electric arc formed in the fuse if the granular gel is activated by drying in open air or in a partial vacuum. The particles of silica gel are full of pores and capable of adsorbing gases rapidly and may serve two general functions in the stopping or quenching of electric arcs formed within the fuse casing. One of these functions is that of the adsorption of the un-ionized or non-conducting metallic vapors surrounding the conducting arc and which have been vaporized from the surface of the fuse conductor by the heat liberated upon the blowing of the fuse. By this adsorption of the un-ionized or non-conducting metallic vapor there is removed from the area of the conducting stream of the arc metallic vapor which otherwise might furnish material which could be further ionized or rendered conducting and thus assist the conducting arc stream to persist. It is possible that the adsorption or absorption of these metallic vapors is materially assisted by the thermal capacity of the gas adsorbing material, which in the case of silica gel is extremely high. Another function which this filling material may perform because of its porous nature and the large surfaces which it presents to gases or vapors is that of causing charged carriers of opposite signs existing in arc streams to come together and discharge their electric charges, thus rendering the arc stream non-conducting. It is well known that oppositely charged carriers in partially conducting gases combine and are discharged, due to the passage of the gases through porous materials. The use of silica gel as a filling material thus insures prompt blowing at the

intended maximum capacity of the fuse, it being impossible for the liberated gases to form with the gel an independent conducting path for the current, as often happens when inefficient or defective fillers are used. Because of the extremely large surface in the form of very fine pores in the particles of silica gel as compared to all other fillers heretofore used, it will be evident to those skilled in the art that a much smaller fuse may be used than has heretofore been possible.

The vents 8 in the fuse casing 2, and the associated paper strip 9 on the inner side of the tube adjacent the vents may be provided, as an additional safety measure. Upon the blowing of the fuse any excess gas which is not immediately adsorbed by the silica gel filler, will disrupt the paper shield 9 and escape through the vents 8, making it impossible for the fuse to explode, and hence eliminating the danger of injury to nearby substances.

It is not intended to limit the invention to the use of a filling material of silica gel, since any other material having highly adsorptive properties may also be used.

What is claimed is:

1. An electric fuse having a filling material comprising a gelatinous gas adsorbing material.
2. An electric fuse having a filling material consisting of silica gel.
3. An enclosed electric fuse having its fuse conductor surrounded by loose, dry particles of silica gel.
4. An enclosed electric fuse of the cartridge type having its fuse conductor surrounded by loose, dry granular silica gel.
5. An electric fuse having its fuse conductor surrounded by loose, dry granular silica gel which has been activated.

In witness whereof, I hereunto subscribe my name this 6th day of Sept. A. D., 1921.

HOMER CLYDE SNOOK.
